UNITED STATES PATENT OFFICE.

MARY K. MORSE, OF PHILADELPHIA, PENNSYLVANIA, EXECUTRIX OF HENRY G. MORSE, DECEASED, ASSIGNOR TO NEW YORK SHIPBUILDING COMPANY, OF CAMDEN, NEW JERSEY, A CORPORATION OF NEW JERSEY.

PORTABLE PUNCHING OR RIVETING MACHINE.

SPECIFICATION forming part of Letters Patent No. 761,528, dated May 31, 1904.

Application filed July 13, 1903. Serial No. 165,276. (No model.)

To all whom it may concern:

Be it known that HENRY G. MORSE, deceased, late a citizen of the United States, residing in the city and county of Philadelphia and State of Pennsylvania, did invent certain new and useful Improvements in Portable Punching or Riveting Machines, of which the following is a true and exact description, reference being had to the accompanying drawings, which form a part thereof.

The invention relates to punching or riveting machines adapted to be supported and transported from above and of such a character as are especially adapted for use in operating upon bent angles, channels, &c.

The object of the invention is especially to provide a simple and effective machine adapted to be used for punching or riveting and in which the upper tool is held stationary and the lower tool moved to or from it to perform the work, this arrangement enabling the position of the tool to be nicely gaged with reference to the work and the work performed with the least possible tendency to error.

The nature of the improvements will be best understood as described in connection with the drawings, in which they are illustrated, and in which—

Figure 1 is a front view of the tool equipped with a punch and die, by which it is adapted to work as a punching-machine. Fig. 2 is a sectional detail taken through the port leading into the cylinder as indicated by the section-line 2 2 of Fig. 1. Fig. 3 is a vertical sectional elevation of the tool, taken as on the section-line 3 3 of Fig. 1. Fig. 4 is a sectional detail through the upper-tool supporting device, taken as on the section-line 4 4 of Fig. 3. Fig. 5 is a side elevation of the upper part of the bail, valve connection, &c., shown partly in section on the line 5 5 of Fig. 6. Fig. 6 is a view of the same parts shown in section on the line 6 6 of Fig. 5. Fig. 7 is a horizontal section on the line 7 7 of Fig. 6. Fig. 8 is a plan view of the trunnioned supporting-frame forming a part of the machine. Fig. 9 is a

front elevation of this frame. (Shown in section on the line 9 9 of Fig. 8.) Fig. 10 is a side elevation of the frame, and Fig. 11 is a sectional view on the line 11 11 of Fig. 8. 50

A indicates the chain by which the machine is supported, the upper end of the chain being usually attached to a crane. The chain is connected by a shackle A' and pin A² with the upper end B' of a supporting-head B, which, as shown, has near its upper end a transverse perforation B², merging into a perforation B³ of larger diameter, forming an interior chamber B⁴, which communicates with a vertical port B⁵, having laterally-extending ports B⁶ 60 B⁷ at its lower end. The head has also formed in it the port indicated at B⁸, said port opening through the side of the head at both ends. In an intermediate position on the head is formed the outwardly-extending annular 65 shoulder, indicated at B⁹, and the lower part of the head is cut away to form the shoulder B¹⁰, continuing below the ports B⁶ B⁷ in the form of a cylindrical extension B¹¹, from the bottom of which depends the threaded portion B¹². 70

C is a pivot-pin fitting in the perforation B² and having its outer end continued in the form of a curve and formed with a perforation therethrough, as indicated at C', the perforation opening into the chamber B⁴ through ports C² and the end of the perforated portion of the pin connecting through a coupling C³ with a conduit C⁴, which in turn connects with a source of pressure fluid. The other end of 80 the pin C (indicated at C⁵) is when placed secured by a head C⁶, which abuts against an annular packing-ring (indicated at C⁷) which fits in the perforation B³. 75

D is a sleeve which fits over the head B and is provided with inwardly-extending shoulders D' and D², which make tight joints with the shoulders B⁹ and B¹⁰. As shown in Fig. 6, the lower portion of the sleeve (indicated at D³) is threaded and when in place has screwed into 90 it the bearing and packing ring, (indicated at F,) the whole being held in place by a nut F',

screwing on the threaded portion B^{12} of the head. A lateral extension of the sleeve has formed in it the ports D^4 and D^5 , the first of which communicates with the lower lateral opening of the port B^8 , while the lower port D^5 communicates with the port B^7 . On the opposite side the sleeve has a bearing-thimble B^6 , communicating through a port with the port D^6 of the head, D^7 indicating an annular bearing which screws into the end of the thimble D^6 and through which passes the end of the tubular bail E , having the annular shoulder E' at its inner end.

G is an exhaust-pipe connecting with the upper lateral opening of the port B^8 .

H is a valve-casing having formed in it the cylindrical valve-chamber H' , opening into a passage in the upper end of the casing, in which is secured the annular ring H^2 , having a central perforation H^3 of the same diameter as the valve-chamber and, as shown, an upwardly-extending flange H^4 , having lateral ports H^5 formed in it, which communicate through a port H^6 with the port B^8 in the sleeve D . Another port H^7 , formed in the valve-casing and opening through the walls of the cylindrical valve-chamber, communicates through the port B^8 of the sleeve D , H^8 indicating a third port formed in the valve-chamber and communicating with the bail I .

J is a piston-valve working in the cylindrical valve-chamber H' and having, as shown, an annular portion J' , which moves from one side to the other of the port H^7 , and above it a cylindrical portion J^2 , which moves partly in the cylindrical chamber H' and partly in the cylindrical perforation H^3 , said cylinder J^2 having a downwardly-depending annular flange J^3 with lateral openings (indicated at J^4) near its upper end. The valve is operated through a valve-lever K' and pivotally supported on a link K , as shown in Figs. 1 and 5.

L is a supporting-frame having extending from one side of it the annular ring L' , which is centrally divided, as indicated at L^7 , by a cut extending through its base and nearly, but not quite, to its top, the base being provided with the perforated lugs L^2 L^3 , through which passes a clamping-bolt M . (Indicated in Fig. 1.)

Extending in opposite directions from the frame L are the trunnions L^3 L^4 , the trunnion L^3 having a central longitudinally-extending perforation (indicated at L^5) opening laterally through ports L^6 , the central perforation communicating with a lateral port L^7 , which extends through a threaded projection L^8 , L^9 indicating a plug to close the end of the longitudinal perforation. The trunnion L^4 is similarly provided with ports, the longitudinal port being indicated at L^6 , the lateral ports at L^7 , and the longitudinal port ending in a chamber L^8 , from which extends a port L^{10} , opening at the top of the ring L' through a slightly-projecting annular extension, (indicated at L^{11} .) The bails E and I connect to common coupling-bases with annular bearings N , which fit on the trunnions L^3 and L^4 , and are provided with annular chambers (indicated at N^2) which communicate through the ports L^6 and L^7 with the ports L^5 L^6 , N^1 indicating a gland by which the packing in the chamber N^2 is secured in place.

O' is a cylinder secured to the ring L' of the frame L by a downwardly-extending annular flange O , O^2 indicating the straight cylindrical part of the cylinder-chamber and O^3 packing-rings secured in the downwardly-extending annular portion O by a gland O^4 .

P indicates the top or head of the cylinder, from the center of which depends the downwardly-extending tool-holding device P' ; P^2 indicating an outwardly-extending annular shoulder near the upper end of the device P' , P^3 a port or passage extending longitudinally from the top of the tool-holder P' , and P^4 a tube passing from side to side through the tool-holder P' and having central ports P^5 , which communicate with the port P^3 . The lower end of the tool-holder, as shown, has an internally-threaded orifice P^6 , into which screws the head P^7 , to which the punch (indicated at P^8 and having a central finger or point P^9) is connected by means of the coupling device indicated at P^{10} .

Q indicates a perforated head screwing into the top of the part P^3 and coupled by a union Q' with a pipe Q^2 , which in turn communicates with the threaded projection L^8 of the frame and through it with the ports L^7 L^5 L^6 and tubular bail E .

R indicates the piston working in the cylinder O' and having an upwardly-extending cylindrical extension R' , which makes a working fit with the annular shoulder P^2 of the tool-holder P' and forms a cylindrical chamber r' between the outwardly-extending shoulder P^2 of the tool-holder and the inwardly-extending shoulder R^2 of the piston.

R^3 is a sleeve extension depending from the bottom of the piston and working between the cylindrical tool-holder P' and the packing-rings held in place by the depending annular extension O of the cylinder.

S is a tool-holder for the lower tool or die, which is secured to the lower portion of the sleeve R^3 , having, as shown, a split ring at its ends, terminating in flanges S' S^2 , which are clamped together by bolts S^3 . The tool-holder is shaped to give convenient passage to the work below the punch or tool P^8 and has a portion S^4 adapted to hold and support the tool or die S^5 beneath the upper tool.

R' is a ring screwing on the end of the sleeve R^3 below the split ring of the tool-holder S and provided with stripping-fingers R^5 R^6 , which when the piston R is in its lowest position extend below the punch P^8 , as shown in Fig. 3.

T , Fig. 3, indicates a spring which, as shown,

has for its chief function the holding in proper place of the cupped leathers at the top and bottom of the cylindrical chamber r' . To the extent of its strength it is obvious that the 5 spring will also operate to push down the piston R and its connected parts, and this is mentioned because of the obvious equivalency of a spring of proper power to the pull-back device, which is actually illustrated and will be 10 hereinafter described.

In normal position the apparatus is suspended from the chain A , as indicated in the drawings, the pressure fluid filling the supply-pipe C' and passing through the curved 15 portion C' of the bearing-pin C and through the port C' into the chamber B' of the head B and through the ports B^5 to the ports B^6 and B^7 . The fluid constantly fills the thimble D^6 and bail E , communicating from said bail 20 through the ports L^6 , L^5 , and L^7 and the conduit Q^3 and head Q , with the longitudinal port P^3 of the upper tool-holder, from said port passing through the lateral ports P^5 of the tube P^4 into said tube and through it into the cylindrical chamber r' , where it acts on the lower shoulder R^2 , formed in the piston, pushing 25 said piston and parts depending thereon, downward to their lowest position, or as shown in Fig. 3. From the other port B^7 , connected 30 with the port B^5 , pressure fluid passes to the port D^6 , and thence to the port H^7 of the valve-casing H , and thence, the valve being in the 35 position shown in Fig. 6, the fluid passes up inside of the flange J^3 of the cylindrical portion J^2 , and out through the lateral ports J^4 into the port H^8 , and thence, through the tubular bail I , to the ports in the trunnion L^4 , and thence through the port L^10 , to the cylinder O' , which is coupled therewith, as shown, 40 by a thimble O^6 , Fig. 2. The pressure fluid acting on the piston R raises it and its sleeve R^3 , the said sleeve carrying upward the tool-holder S , and stripping-fingers R^5 , and brings the tools S^4 and P^8 into operation upon the 45 plate, which, of course, is situated between them. When the work is effected, the valve J is moved upward, the portion J' cutting off the supply of pressure fluid and the cylindrical portion J^2 moving upward in the annular ring H^2 until the lateral ports J^4 open on the upper side of said ring, when the fluid 50 from the cylinder is free to flow backward through the bail I , port H^8 , ports J^4 , and ports H^6 , into the port H^6 of the casing, whence it passes through the ports D^4 and B^8 to the exhaust-pipe G . The weight of the parts depending on the piston will of course tend to draw the piston down, the resistance of the work or from other sources being overcome 55 by the constant fluid-pressure in the cylinder r' , which thus acts as a pull-back cylinder.

The stripping-fingers R^5 R^6 press against the work as the piston R and sleeve R^3 move down and press it off the punch P^8 .

Having now described the said invention,

what is claimed as new, and desired to be secured by Letters Patent, is—

1. In a portable machine for operating punching or riveting tools, means for holding the upper tool, said means being secured to 70 and moving with the machine-supporting devices, in combination with a U-shaped holder for the lower tool suspended and vertically movable on the holder for the upper tool, and means for imparting to the said U-shaped lower-tool holder a vertical motion with respect to the upper-tool holder. 75

2. In a portable machine for operating punching or riveting tools, a cylinder directly supported on and moving with the mechanism 80 for moving the machine in combination with a support for the upper tool secured to said cylinder, a piston moving in said cylinder and a holder for the lower tool supported on and moving with said piston. 85

3. In a portable machine for operating punching or riveting tools, a cylinder directly supported on and moving with the mechanism for moving the machine, in combination with a support for the upper tool secured to said 90 cylinder, a piston moving in said cylinder, a holder for the lower tool supported on and moving with said piston and a stripping device also supported by and moving with the piston. 95

4. In a portable machine for operating punching or riveting tools, a cylinder directly supported on and moving with the mechanism for moving the machine, in combination with a support for the upper tool secured to said cylinder, a piston moving in said cylinder, a holder for the lower tool supported on and moving with said piston and pull-back mechanism other than the cylinder and piston aforesaid for forcing the lower-tool holder downward. 100

5. In a punching or riveting machine, the combination with means for supporting and transporting the machine from above, of a cylinder directly supported by said means, a tool-support depending from the top of said cylinder and extending through its bottom, an annular piston moving in said cylinder and on said tool-support, a depending sleeve extension from the piston extending through the bottom of the cylinder and a tool-holder head secured on said sleeve. 110

6. In a punching or riveting machine, the combination with means for supporting and transporting the machine from above of a cylinder directly supported by said means, a tool-support depending from the top of said cylinder and extending through its bottom, an annular piston moving in said cylinder and on said tool-support, a depending sleeve extension from the piston extending through the bottom of the cylinder, a tool-holder head, secured on said sleeve and extending below the tool-holder secured to the cylinder and a stripping device also secured to the sleeve. 125

7. In a punching or riveting machine, the combination with means for supporting and transporting the machine from above, of a cylinder directly supported by said means, a 5 tool-support depending from the top of said cylinder and extending through its bottom, said tool-support having an annular shoulder P^2 extending into the cylinder and a port P^3 formed therein and connecting through its 10 side with the space below said shoulder, an annular piston moving in said cylinder and upon the tool-holder, said piston having a cylindrical extension R' fitting on the annular shoulder B^2 , a depending sleeve extending 15 from the piston through the bottom of the cylinder, and a tool-support secured to the sleeve and extending beneath the tool-support secured to the cylinder.

8. In a punching or riveting machine, a 20 trunnion-frame L having its trunnion L^4 formed with ports l^5 l^6 and a port L^{10} leading

therefrom to the top of the frame in combination with bails E I connecting the trunnions of the frame with an overhead support, the bail I consisting of a conduit connecting with the 25 ports in trunnion L^4 , a valve connected with the bails and regulating the admission and exhaust of pressure fluid to the conduit-bail I , a cylinder supported on frame L and having its bottom connected with port L^{10} , a tool-supporting cylindrical extension from the top of the cylinder reaching through the bottom thereof, a piston moving in the cylinder and on the tool-supporting extension, a depending sleeve extension from said piston and a tool- 30 support secured thereto.

MARY K. MORSE,
Executrix of the estate of Henry G. Morse.
